BLOCK SYSTEM

Matthew H. Loughridge, Bogota, N. J.

Application March 13, 1939, Serial No. 261,403

15 Claims. (Cl. 246—62)

This invention relates to block systems for controlling traffic on a railway track and it is shown in connection with electric railways which are provided with a third rail or power conductor for supplying propulsion current to the trains. An object of the invention is to superimpose the block system upon the power system so that trains may be continuously controlled as they move along the track. Another object of the invention is to impress a block circuit upon sections of the power conductor for controlling trains and to suppress this circuit by a controlling circuit connected with another section of the power conductor; another object of the invention is to provide a block system superimposed upon a power conductor which is divided into sections and which stops a train in the rear block when the next block ahead is occupied, and which also stops the last train entering an occupied block; another object of the invention is to provide a block system superimposed upon a power conductor which is adaptable for traffic in both directions on the same track; another object of the invention is to provide a selective block system superimposed upon a power conductor without the use of moving apparatus on the trackway, and another object of the invention is to provide a block system for electric railways having a power conductor divided into block sections and in which control of the train is obtained through the trolley or shoe which collects the current for the propulsion system.

These and other objects of the invention will be more particularly understood from the following specification and the accompanying drawings, in which

Fig. 1 is a circuit diagram showing one form of the invention operated by tuned circuits;

Fig. 2 is another form of the invention operated by rectified circuits and arranged to provide protection against a following train entering an occupied block;

Fig. 3 is another circuit diagram in which the block current is supplied by a separate transmission line;

Fig. 4 is a diagram of the apparatus and circuit in Fig. 2 showing the operation on a train in rear of an occupied block;

Fig. 5 is a circuit diagram of a combined block system and power system applied to a track for traffic in both directions.

This system disclosed in Figs. 1 to 5 inclusive was originally disclosed in part in application Serial No. 594,771, filed February 24, 1932, now Patent 2,151,709, March 28, 1939. This application

embodies the block system with the power distribution system in such a way that contact wires or inductive devices for the block system itself are not necessary, while a continuous block control is obtained. According to established practice at the present time the operating power for electric cars is obtained from a trolley wire or from a third rail by contact, and the same contact can be used to pick up the train control circuit and selectively operate a train control system which is superimposed on the power wire.

Generally considered, this system comprises dividing the power wire by the use of reactance devices in such a manner as not to materially interfere with the propulsion current, while, at the same time, the train control current is limited by these divisions. A current having a particular characteristic which is selectively different from the current in the power wire is superimposed on each section of the power wire and is arranged to energize a train control relay in a resonant circuit on the vehicle to permit the vehicle to proceed. The source of this current is controlled by a current having another characteristic or frequency connected with the block ahead and is so arranged that a train in the block ahead substantially depresses, or deenergizes, the superimposed train control current and thereby causes a train in the following block to be stopped.

The system uses currents of three different frequencies or characteristics, i. e.: (a) the propulsion current has one characteristic; (b) the train control current has a second characteristic and (c) the block control current has a third characteristic. For instance, the propulsion current may be direct current or may be alternating current of a commercial frequency, such as sixty cycles per second. The train control current which is superimposed upon the power wire may have a frequency of at least one thousand cycles per second, and the control of this circuit may be embodied in a circuit having one-half this frequency.

45 The system is operated by providing a high frequency line with a transformer connected between this line and the running rails for each block. The secondary of this transformer is used to energize the primary circuit of a second transformer, and the secondary of the second transformer is used to energize a portion of the power wire in the rear with train control current. The primary circuit of the second transformer is bridged across the power wire and the track rails. Each of the circuits are connected through con-

densers to establish a predetermined resonance. The vehicle is provided with a propulsion motor and a train control relay controlled by the train control current. This relay, when energized, permits the vehicle to proceed and when deenergized causes a brake application. A circuit is provided on the vehicle connected with the trolley wire which is resonant to the train control current and has a translating device embodied therein which is energized as long as this current is present in the power wire. A controlling circuit is connected with the trolley contact which is resonant to the primary circuit of the second transformer and practically deenergizes or suppresses this circuit when the train is in the block, thereby effectively deenergizing the power wire in the rear block of train control current, thus establishing conditions to stop the train in the rear block.

The track wiring

In the drawings, the track rails are indicated by 11, the power or trolley wire is indicated by 12, a low frequency generator is indicated by 13 for energizing the power wire 12 and which is grounded on the track rails by wire 14. The power wire is divided into block sections, *a*, *b* and *c* by the reactances 15a, shown as of the coil type. High frequency generator 16 energizes the transmission wire 17 and has the opposite side grounded on the track rails by wire 14. A transformer 20 is provided for each block having a primary coil 18 connected between the high frequency transmission line 17 and the ground or rail return 19. This transformer is provided with an output circuit from secondary winding 21 which energizes the input circuit of transformer 24 through coil 22. The secondary coil 23 in the output circuit of transformer 24 is grounded on one side through wires 25 and 19 and on the opposite side connects through the condenser 26 and the line wire 27 to the block in the rear on the power wire 12.

The input circuit for primary coil 22 of transformer 24 is connected at one side to the ground wires 25 and 19 and connects on the opposite side through wire 28 and condenser 29 and wire 27 to the trolley wire. This connection is made to the block section of the trolley wire immediately in advance of the block section which is energized through the secondary coil 23 of the output circuit of transformer 24. The circuits described connecting on one side to the power wire 12 and on the opposite side to the track rails are completed on the cars between conductors 32 and 33 and selectively operate apparatus to control the cars as hereinafter described.

The current which operates the motors of the train, in the power or trolley wire will be referred to as the propulsion current; the current in the power or trolley wire which energizes the train control relay will be referred to as the train control current and the current in the power or trolley wire which controls the train control current in an adjoining block will be referred to as the block control current.

The car wiring

The car wiring is indicated at 31 in which the conductor 32 picks up propulsion current from generator 13 on the power wire or third rail. This is controlled by contact 35 of train control relay 34, by wire 36 to motor 37 and by contact 33 to ground on the running rails. This completes the propulsion circuit. When relay 34 is

energized the motor circuit is established and the vehicle proceeds; when this relay is deenergized the motor circuit is interrupted at 35 and the vehicle stops. The relay 34 may control the brakes as well as the power in a system corresponding with U. S. Patent 1,805,551, issued May 19, 1931 to M. H. Loughridge.

A primary train control relay 42 is controlled by the train control circuit connected with the trolley contact 32 and wire 40 to coil 45, wire 46, primary coil 47 of transformer 49 and condenser 48 to the ground connection 33. This completes the train control circuit from transformer 24. The transformer 49, through condenser 50, energizes the coil 51 of relay 42. Relay 42, as shown, is of the motor type and when coils 51 and 45 are energized with current in proper phase relation this relay closes the contact 41, connecting wire 40 with 43 and energizing the train control relay 34 which connects by wire 44 with the return circuit at 33.

In the system described the condensers 48 and 50 are attuned to correspond with condenser 26 in the train control circuit so that when high frequency current is present in this circuit the relay 42 is moved to the energized position and thereby establishes the motor circuit to permit the vehicle to proceed. On the other hand, when this current is absent from a block section, or is substantially suppressed, the relay 42 is deenergized and the vehicle is stopped.

It will be observed that when a train is in the block the primary coil 22 of transformer 24 is short circuited through condenser 29 by a circuit starting on wire 28, condenser 29, wire 27, block section or power wire 12, trolley contact 32 on vehicle 31 and motor circuit to ground return through 33 and 19. Also when the train control relay 34 is deenergized by a train in the block ahead a circuit is established through contact 35 and wire 38 with the condenser 39 which is grounded at 33. This establishes the block control circuit. The condenser 29 and the condenser 39 are made resonant to each other, and the condenser 29 is also resonant to the motor circuit. The condenser 29 when thus connected in circuit with the vehicle circuit suppresses the primary circuit of 24 to such an extent that the rear block circuit fed by this transformer is substantially deenergized and the block in the rear is deprived of block current. The transformer 20 is preferably of the open circuit type so that the output of the secondary is definitely limited.

The reactance coils 15a are provided to substantially isolate the high frequency block current to each section of the power wire without materially interfering with the power circuit whether it is energized by direct or alternating current. Reactances for this purpose are commonly used in the art one form of which is shown in U. S. Patent 905,327, December 1, 1908.

The system described includes the fundamental principles of the system in which a different characteristic is obtained between the train control current and the block control current by a system of resonance so arranged that while the train control current for the rear block is substantially suppressed, the train control current from the next block ahead remains effective to energize the train control relay and permit the train in the forward block to proceed while preventing a following train in the rear block from proceeding. It will be noted that current is required to produce the proceed effect thus operating by the closed circuit principle. In opera-

tion, the static apparatus on the trackway remains energized electrically from the generators. When a train enters a block with the preceding block clear, the train control relay 34 is energized through the primary train control relay 42 which is energized by the train control current in the block section which the train occupies. This condition continues from block to block under clear conditions. Relay 34 energized, supplies propulsion current from the conductor 12 through contact 32 to the propulsion motor 37 thereby providing for the continuous forward movement of the train.

When a second train follows another train and remains at least a clear block in rear of the leading train, it continues to move forward from block to block in the same manner as the leading train on a clear track. When a following train closes up on the train ahead by entering the block immediately in the rear of the train ahead, the train control relay 34 on the following train is deenergized because the train in the forward block has shunted the input circuit of transformer 24 and suppressed the train control circuit of the block occupied by the following train. Relay 34 opens the circuit of the propulsion motor and thereby stops the following train, which, in ordinary practice is stopped within the block. When the leading train moves on to the next block ahead the shunt on the input circuit of transformer 24 is removed, the train control current is restored to the block section of wire 12, this energizes the train control relay on the rear train and it resumes its normal running. If the train in the forward block is stopped the shunt of the input circuit of transformer 24 is maintained through 35 and 39 to suppress the train control current to the rear block and stop the train in this block.

Selection by rectifiers on the track

A modified arrangement is shown in Fig. 2 in which the block current is made selective by feeding through two sets of full wave rectifiers with a corresponding increase of frequency, and the vehicle circuits are so arranged that a train in the rear block is not only controlled by a train in the next block ahead, but if the following train should enter an occupied block it will be stopped until the train ahead occupying the block has moved out.

The track wiring includes the trolley wire 12 divided into block sections *a*, *b*, *c* by the coil type of reactance 5a. The first transformer 20 is energized from the line wire 17 by current of a higher frequency than the propulsion current in the trolley wire. The secondary coil 21 of transformer 20 connects to the full wave rectifier 90 and this rectifier, through condenser 91, energizes the second transformer 92 which is used to energize a third transformer 93 through the rectifier 97 and the condenser 99 so that the frequency of the current output from the secondary from transformer 93 is double that of current input of transformer 92 as will be understood from the diagram. The secondary of 93, through condenser 26 energizes the block circuit 27 with train control current.

In this arrangement the transformer 111 is provided on the vehicle for the propulsion current, the secondary of which is controlled by the train control relay 34 to energize the motor 137 through contact 35. Relay 114, grounded on one side at 33, connects through condenser 112, reactance 61 and conductor 32 to the power wire

12. The condenser 112 is in resonance with the condenser 29 so that relay 114 is energized from the secondary coil 21 of transformer 20, that is, from the block control circuit, the suppression current of the control circuit being sufficient to energize relay 114 while effectively suppressing the energy to transformer 92.

A transformer 117 has a primary coil, one side of which is grounded at 33, the other side connects through wire 118 to conductor 32 and, for tuning purposes, a second condenser 119 may be bridged across this coil as shown. The secondary of transformer 117, through circuit 116, energizes relay 115. This circuit is resonant to the train control current from condenser 26 and relay 115 is energized when train control current is present and is deenergized when the train control current is suppressed.

A stick relay 120 is provided to insure that a train receiving a proceed effect in a block from the train control circuits will not be influenced by a following train entering the same block. Relay 120 is energized from battery 121, through contact 122 of relay 114 energized, wire 123, relay 120 and wire 124 to battery. The stick circuit of relay 120 is maintained through contact 127, wire 126 and contact 125 of relay 115 to battery. The block relay 34 is energized from battery 121 through contact 128 of relay 115, wire 129, contact 130 of relay 120, wire 131, relay 34 and wire 124 to battery.

In operation, when the next block ahead is clear, the relays 114 and 115 are energized, the stick relay 120 is energized and the train control relay 34 is energized enabling the train to proceed. When another train enters the block in rear of an occupied block the relay 115 on the rear train is deenergized also relay 34 which opens the motor circuit and, normally, the rear train is controlled and stopped within the rear block where it remains until the block ahead clears and the train control current is restored to the block sections. Should the rear train, for any reason, overrun the block and enter the block ahead already occupied by another train, this would put a second shunt on the control circuit and thereby would deenergize relay 114 in both of the trains occupying the same block due to the limited output of 21. In the rear train, however, the relay 115 was deenergized when the occupied block was entered and this relay is made slow acting in its pick up so that relay 114 becomes deenergized before relay 115 can pick up, thereby deenergizing the stick relay 120 on the rear train and maintaining the train control relay 34 deenergized to stop this train. As relay 114 controls the pick-up circuit of the stick relay 120, it is apparent that 120 cannot become energized after the relay 115 is energized until relay 114 is again energized. It will be noted, however, that on the advance train already in the block relay 115 is energized and the holding circuit of relay 120 is thereby established so that should relay 114 on this train become deenergized it would have no effect on the control of the train. This enables the first train to continue its journey while the second train is controlled until the track clears. A railway system having superimposed frequencies on a track circuit is shown in U. S. Patent 1,626,928.

Relays 114 and 120 are provided for the control of a following train in the same block with another train. Where this control is not desired, these relays are omitted and the primary train control relay 115 controls the secondary

train control relay 34 by the circuit on wires 129 and 131, omitting the control by relay 120.

In the arrangement described, frequency changes on the trackway were obtained by static apparatus. It is apparent, however, that a wider range of frequency to distinguish between the block control circuit and the train control circuit may be obtained by the use of separate transmission lines, each energized with a different frequency range. For instance, in Fig. 3 the transmission line 101 may be energized with current having a frequency of 10,000 cycles and which can be used to energize the train control circuit while the transmission line 17 may be energized with a frequency of 1,000 cycles and is used to energize relay 104 through rectifier 90 controlling the block control circuit. Relay 104, by contact 103, connects the block wire 27 with the transmission line 101 through the condenser 102. A transformer, however, may be substituted for this condenser where the design of the circuit shows that a transformer is preferable.

Wayside apparatus responding to the presence of block current in the power wire may be provided as indicated by the relay 144 which, through the transformer 142, is connected with the power wire 12 by connection 140, condenser 141, and is connected to the ground return wire 143. The condenser 141 is made resonant to the current in the train control circuit controlled by condenser 102. Relay 144 controls the translating device 146 to show the condition of the block. The electric device 146 controlled by relay 144 may be a light bulb giving an indication for the purpose desired.

The trolley wire 32 is connected with ground 33, through condenser 135 and conductor 33. This effectively suppresses the input circuit of rectifier 90 through condenser 29 and deenergizes relay 104 and the rear block of train control current. Relay 136 connects through transformer 117 the primary of which is grounded on one side at 33 and connects with condenser 119 and conductor 32 on the other side to respond to the train control current in the transmission line 101. Relay 136 closes the circuit of relay 34 through wire 138, contact 137, wire 32, to the power wire 12 and return through 124 and ground contact 33.

The operation of the system in Fig. 3 corresponds with Fig. 1. A train in the block shunts the input circuit of rectifier 90 thereby deenergizing the rear block of train control current by deenergizing relay 104. A train entering the rear block at this time will have its train control relay 34 deenergized owing to the absence of train control current in this block. This stops the rear train until the block ahead is cleared and the shunt removed from rectifier 90.

It should be understood that the circuit is regarded as deenergized when the translating device in the circuit has changed its position or ceases to operate in the manner in which it operates when normally energized, although the circuit itself may not be deenergized in the sense in which it would be deenergized if the circuit were open.

The block system herein disclosed has been shown in connection with an electric propulsion system. It is to be understood, however, that the block system may be applied by itself to trains that have self-contained motive power. It is also to be understood that in the latter case block sections of the block wire can be insulated

from each other, thereby simplifying the electric apparatus.

The apparatus and circuits in Fig. 4 correspond with Fig. 2 and operate in the same manner. In this figure train 31a occupies section *a* and train 31b occupies section *b* of the block ahead. The primary train control relay 115 on the following train 31a is deenergized owing to the presence of train 31b in the preceding block. This deenergizes the secondary train control relay 34 and opens the circuit of motor 137 at 35 thereby stopping the motor.

The electrical apparatus used in carrying out this invention should be designed for the circuits in which the apparatus is used. This depends upon the character and the extent of the current necessary for propulsion purposes, the length of the block sections and the frequency of the current in the train control circuit, also the frequency of the current in the block control circuit. The figures used in describing the system are arbitrary figures for illustration only.

Single track operation

A system designed for single track operation is shown in Fig. 5. In this arrangement, in addition to using resonant circuits, a change of frequency is obtained between the train control circuit and the block control circuit in which the frequency of the train control circuit is double that of the block control circuit thereby insuring greater reliability in the selection of control between the block control and the train control circuits. This system also includes a line controlled relay which changes over the train control conductor from the block in the rear to the block in advance, or vice versa, according to the established direction of traffic, thus adapting the system for traffic in both directions on the same track.

The power wire 12 is provided with reactances 15a of the coil type for separating the block sections and may be energized with direct current. The output circuit of secondary coil 21 of transformer 20 energizes the transformer 92 through the full wave rectifier 90 and the condenser 91. The secondary of transformer 92, by reason of the full wave rectifier 90, has twice the frequency of the current in the secondary coil 21. The secondary of transformer 92 connects through condenser 93 with the contact finger 88 of line relay 86. When this contact is in the left hand position as shown, wire 27 to the left is energized from transformer 92 and connects through the contact finger 89 of relay 86 in the next block and through wire 94 to the block section of the power wire. This energizes the block section with train control current.

When the contact fingers of the line relays 86 are moved to the right hand position, the transformer 92 is connected with the line wire 27 to the right and the line wire 27 from the left connects to the block section of the power wire by wire 94. Relays 86 thus establish conditions for traffic in either direction.

The line relays 86 are polarized and the contact fingers 88 and 89 are swung to the right or to the left in accordance with the polarity of the circuit energizing these relays. This circuit established through line wire 85 is controlled by manually operated switch 84 which, in one position, connects to battery 82 and in the other position connects to battery 83. These batteries are of reversed polarity and are grounded on the track rails through wire 81. The relays 86 are

grounded through connections 87 and 19. This enables the direction of traffic to be established by the position of switch 84. When it is desired to control the train control circuit by any trackway condition; as, for instance, by the position of a trackway switch, this control may be obtained by a switch 27a in wire 27 connected with the controlling function.

The vehicle circuit in Fig. 5 includes a reactance 61 in the trolley conductor 32 and a condenser 62 in series with the reactance 61 connecting to the ground at 33. The transformer 64 is connected to conductor 32 above the reactance 61 and is grounded by wire 65; a condenser 65 is bridged across the primary of this transformer. The output circuit of secondary coil 67 of transformer 64 is connected to the grid 68 of an electron amplifier, the opposite side being connected to filament 71 which is heated by battery 70. A circuit is established from the plate of this amplifier through conductor 72, condenser 73 and reactance 74 in multiple, battery 75, transformer 76, and return to the electron tube through the filament in accordance with established practice. This energizes secondary coil 77 which, through rectifier 78 and circuit 79, energizes the train control relay 34, permitting the vehicle to proceed.

The condenser 62 is resonant to the control circuit including the condenser 29 and the condensers 65 and 73 are resonant to the train control circuit including condenser 93. With a train in block *b*; for instance, the block control circuit is suppressed by a shunt place on the input circuit of transformer 92 through wire 28, condenser 29, wire 95, block section *b*, conductor 32, reactance 61, condenser 62, and ground return by 33 and 19. At the same time the train control current in section *b*, being of a higher frequency than the block current, is opposed by reactance 61 and energizes the train control relay 34 through the amplifier. This permits a train to proceed in block *b* while the block current to train control *a* is suppressed, due to the shunting of the input circuit of transformer 92. Thus a train in block *a* will be stopped while another train occupies block *b* when traffic is moving from left to right.

When switch 84 is reversed the armatures of the relays 86 at each location are reversed or moved to the right hand position to adjust the system for traffic from right to left. In this case the train control current from 92 controlled by contact finger 88 connects to conductor 27, leading to the right, and through contact finger 89 of relay 86 in the next block to the right it connects to the block section of the power conductor 12 by wire 94. In this case a train in block *a* for instance moving towards the left shunts the block circuit from 92 through 88 to the right and wire 27 which is feeding block *b* to the right by 28, 29, 95, 94, through the vehicle circuit and return by wire 19 so that a following train in block *b* is stopped until block *a* clears.

Having thus described my invention, I claim:

1. In a block system, a railway track, a power conductor adjacent said track, reactances operatively associated with said conductor dividing said conductor into block sections, a source of alternating current supply, a transformer connected with said supply, a block control circuit energized by said transformer and connected to a section of said power conductor, a train control circuit having current with a characteristic difference from the current in said controlling cir-

cuit and controlled by said controlling circuit and connected to a block section of said power conductor adjacent the section energized by said block control circuit, the other side of said controlling circuit and said block control circuit being connected to the track; a vehicle on said track operated by said power conductor, a circuit on said vehicle co-operating with the section of said power conductor and completing the circuit between said conductor and the track and to which the controlling circuit is connected for suppressing said controlling circuit, and means on the vehicle responsive to the current in said train control circuit controlling the operation of said vehicle.

2. In a block system, a railway track, a conductor adjacent said track electrically divided into sections, means for energizing each section with train control current of a particular characteristic, means for energizing each section with block control current having a second characteristic, each of said means connected on one side to the track, said block control current for one section controlling the train control current for an adjoining section, a vehicle on said track having a circuit including a section of said conductor and completing the circuit between said conductor and the track, and means in the vehicle circuit selectively responsive to said train control current and controlling the movement of the vehicle on the track, said block control current being shunted by said vehicle circuit.

3. In a block system, a railway track, a conductor adjacent said track electrically divided into sections, means for energizing each section with train control current of a particular characteristic and with block control current having a different characteristic, each of said means connected on one side to the track, said block control current controlling the train control current for an adjoining block, a vehicle on the track having a circuit including a section of said conductor completing the circuit between the conductor and the track, and translating means in said vehicle circuit selectively responsive to said train control current for controlling the operation of the vehicle, said block control current being shunted by said vehicle circuit.

4. In a block system, a railway track, a conductor adjacent said track electrically divided into sections, means for energizing each section with train control current of a particular characteristic and with block control current having a different characteristic, each of said means connected on one side with the track, said block control current controlling the train control current for a different section of said conductor than the section which it energizes, a vehicle on the track having a circuit completing the circuit between said conductor and the track, means in the vehicle circuit cooperating with said block control current for deenergizing the train control circuit, and translating means on the vehicle selectively responsive to said train control current controlling the operation of the vehicle.

5. In a block system, a railway track, a conductor adjacent said track electrically divided into sections, a train control circuit for energizing each block section with current of a particular characteristic, a transformer for energizing said train control circuit connected on one side with the track, an input circuit for said transformer having controlling current of a different characteristic from said train control cir-

cuit, one side of said input circuit connected to the track and the other side connected to an adjacent section of said conductor from the section energized by the train control circuit, and a vehicle on said track having a circuit co-operating with each section of said conductor to complete the circuit of the controlling current to the track, thereby suppressing the input circuit of said transformer and deenergizing the train control circuit.

6. In a block system, a railway track, a conductor adjacent said track electrically divided into sections, a source of high frequency current, a first transformer connected with said source and having a first output circuit, one side of which is connected with a section of said conductor and the other side is connected to the track, a second transformer energized from said first output circuit and having a second output circuit, a train control circuit for energizing the section of said conductor adjacent the section connected with the first output circuit and energized from said second output circuit, a vehicle on said track having a circuit completing the circuit between said conductor and the track and completing a shunt for the first output circuit to deenergize the train control circuit.

7. In an electric railway system, the combination, a conductor adjacent the trackway supplying current for propulsion purposes, means electrically dividing said conductor into block sections, a train control circuit superimposed on each section of said conductor, a transformer having a first output circuit for energizing said train control circuit, an input circuit for energizing said transformer with current having a characteristic different from said train control current, said input circuit connected on one side with a section of said conductor adjacent the section energized by said first output circuit and connected on the other side with the track, and a vehicle on the track operated by said propulsion current and having a circuit with a translating device controlling the vehicle and completing the train control circuit from said conductor to the track and completing a shunt circuit from said input circuit to deenergize the train control circuit.

8. In an electric railway system, the combination, a conductor adjacent the trackway supplying current for propulsion purposes, means electrically dividing said conductor into block sections, means for superimposing on each block section a train control current having a particular characteristic, means for superimposing on each section a block control current having a characteristic different from the train control current and the propulsion current and controlling the train control current for an adjoining block, each of said means connected on one side with the track, a vehicle on the track having a motor operated by said propulsion current and having a circuit between said conductor and the track, and means in the vehicle circuit selectively responsive to said train control current for controlling the vehicle motor, said vehicle circuit shunting said block control current.

9. In a block system, a railway track, means electrically dividing the trackway into blocks, a train control circuit on the trackway energized by current of one frequency, a block control circuit on the trackway energized by current of a lower frequency and controlling said train control circuit for an adjacent block, said train control circuit and said block control circuit each

connected on one side to the track, a vehicle on said track having a circuit, means establishing electrical connection between the vehicle circuit, said train control circuit and said block control circuit, a translating device in the vehicle circuit selectively energized by said train control circuit and controlling the vehicle, and means in the vehicle circuit for shunting said block control circuit to deenergize the train control circuit.

10. In a block system, a railway track, a power conductor on the trackway, electrical means associated with said conductor dividing it into block sections, a transformer energized by alternating current, a block control circuit energized by the output circuit of said transformer, a train control circuit controlled by said block control circuit and energized by current differing in character from said controlling circuit, means connecting said train control circuit to one section of said power conductor, means connecting one side of said block control circuit to the section of said conductor in advance of the section to which the block circuit connects and the other side to the track, a vehicle on said track connecting with said power conductor, a propulsion motor on said vehicle energized by current from said power conductor, a train control relay controlling said motor, a circuit on said vehicle connected with said power conductor attuned to said block circuit and controlling said train control relay and a second circuit on said vehicle connected with said power conductor attuned to said block control circuit and arranged to shunt said block control circuit to deenergize said train control circuit.

11. In a block system, a railway track, a power conductor on the trackway, electrical means associated with said conductor dividing it into block sections, a limited output transformer, energized by alternating current on the trackway, a block control circuit energized by said transformer, a train control circuit controlled by said block control circuit and energized by current differing in character from said block control circuit, means connecting said train control circuit to one section of said lower conductor, means connecting said block control circuit to the section of said conductor in advance of the section to which the train control circuit connects, a vehicle on said track having a circuit connecting with said power conductor, a propulsion motor on said vehicle energized through the vehicle circuit by said power conductor, a train control relay controlling said motor, a circuit on said vehicle connected with said power conductor attuned to said train control circuit and controlling said train control relay and a circuit on said vehicle including said power conductor and the railway track shunting the output of said transformer.

12. In a block system, a railway track, a power conductor on the trackway, electrical means associated with said conductor dividing it into block sections, a transformer energized by alternating current on the trackway, a block control circuit energized by the output circuit of said transformer, a train control circuit controlled by said block control circuit and energized by current differing in character from said block control circuit, means connecting said train control circuit to one section of said power conductor, means connecting one side of said block control circuit to the section of said conductor in advance of the section to which the train

control circuit connects and the other side to the track, a vehicle on said track having a circuit connecting with said power conductor, a propulsion motor on said vehicle energized by said power conductor, a block relay, a shunt relay and a stick relay on said vehicle, said train control relay being energized by said train control circuit, said shunt relay being energized by said block control circuit and said stick relay having a pick-up circuit controlled by said shunt relay and a stick circuit controlled by said train control relay and the circuit of said motor being established by said stick relay and by said train control relay in the energized positions.

13. In a block system, a railway track, a power conductor on the trackway, electrical means associated with said conductor dividing it into block sections, a transformer energized by alternating current for each block, a block control circuit energized by the output circuit of said transformer, a train control circuit controlled by said block control circuit, and energized by current differing in character from said block control circuit, means connecting said train control circuit to a section of said conductor, means connecting one side of said controlling circuit to a section of said conductor and connecting the other side to the track, the block control circuit being connecting to the section in advance of the section where the train control circuit connects, a vehicle on the track having a circuit connecting with said power conductor, a propulsion motor on the vehicle, a train control relay controlling said propulsion motor, a circuit embodied in said vehicle circuit controlling said train control relay connected with the train control circuit in said conductor, a shunt circuit for said block control circuit connected with said conductor and means on each vehicle controlled by said train control relay for stopping the vehicle when it enters a block already occupied by another vehicle.

14. In a block system, a railway track, a power conductor on the trackway, electrical means associated with said conductor dividing it into block sections, a transformer energized by al-

ternating current, a second transformer energized from the output circuit of the first transformer through a rectifier, a train control circuit energized from said second transformer and connected with a section of said conductor, a block control circuit connected in shunt with the output circuit of said first transformer before it is rectified, connected on one side with the section of said conductor ahead of the section connected with the train control circuit and on the other side with the track, a vehicle on the track having a circuit connecting with said power conductor, a propulsion motor on said vehicle, a circuit on the vehicle having a train control relay energized by said train control circuit controlling the circuit of said motor, and a selective shunt on said vehicle for said block control circuit.

15. In a block system, a railway track arranged for traffic in both directions, a power conductor on the trackway, electrical means associated with said conductor dividing it into block sections, a line conductor, a relay connected with said line conductor for each block, a transformer energized by alternating current, a second transformer energized by the output circuit of the first transformer, a train control circuit energized by the output circuit of the second transformer, a block control circuit energized by current differing in character from the train control circuit, connected on one side with a section of said conductor and on the other side to the track, said train control circuit controlled by said relay and connected to said conductor so that the train control circuit connects to a section immediately in rear of the section where the block control circuit connects for traffic in either direction on the track, a vehicle on the track having a circuit connecting with said power conductor, a propulsion motor on said vehicle, a circuit on the vehicle having a train control relay energized by said train control circuit controlling the circuit of said motor, and a selective shunt on said vehicle for said block control circuit.

MATTHEW H. LOUGHridge.

CERTIFICATE OF CORRECTION.

Patent No. 2,255,797.

September 16, 1941.

MATTHEW H. LOUGHRIDGE.

It is hereby certified that error appears in the printed specification of the above numbered patent requiring correction as follows: Page 6, second column, line 47, for "lower" read --power--; and that the said Letters Patent should be read with this correction therein that the same may conform to the record of the case in the Patent Office.

Signed and sealed this 17th day of February, A. D. 1942.

(Seal)

Henry Van Arsdale,
Acting Commissioner of Patents.
